UNITED STATES PATENT OFFICE.

JOHN ROBERT McFARLIN, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

LIGHTNING-ARRESTER.

1,276,783.

Specification of Letters Patent. Patented Aug. 27, 1918.

Application filed July 14, 1917. Serial No. 180,495.

To all whom it may concern:

Be it known that I, JOHN ROBERT McFARLIN, a citizen of the United States, residing at Philadelphia, in the county of Philadelphia and State of Pennsylvania, have invented certain Improvements in Lightning-Arresters, of which the following is a specification.

My invention is more particularly an expulsion type lightning arrester and my primary object is to provide improved means of high efficiency and flexible action, as well as simple, convenient and durable construction, for protecting electrical apparatus 10 from lightning and other high voltage discharges, by carrying such discharges to ground, and effectively preventing a following flow of line or dynamic current.

A characteristic feature of my device is its 20 peculiar means by which the force acting to stop the discharge increases with the flow, relatively small flow of current being stopped by the resistance in its path and the heavier flows by a proportionate blast 25 through a main air gap forming an outlet for a housing containing serially arranged air gaps together with a resistor.

A desideratum of the construction is its 30 elimination of thrust upon the housing by coupling together in interdependent relation the resistor and devices for forming the air gaps and connecting them in movable relation to their bearings.

My improvements, in their preferred 35 form, are comprised in an insulating housing having a sealed top, containing a plate electrode provided with clips connected with the lead from the line wire, and a sealed bottom provided with an opening containing 40 a tubular electrode connected with the ground wire, in combination with a resistor having its top movably engaged by the clips, an insulating bolt engaged to the resistor as by a conducting clamp, a series of dished 45 conducting rings, together with a series of insulators, disposed on said bolt to form a plurality of spark gaps in series with the clamp and resistor, and a conducting stem and terminal screwed on the bolt so as to 50 clamp the conducting rings and insulators together in the desired relation to the resistor, the stem having a shoulder or head resting on an insulating bearing in the bottom of the housing, whereby such stem, to-

gether with its connections, are supported 55 and held in position in the housing with the stem disposed in the tubular electrode to form a spark gap therewith.

The characteristic features of my invention are fully disclosed in the following description and the accompanying drawings in illustration thereof.

In the drawings, Figure 1 is an elevation of a lightning arrester embodying my improvements; Fig. 2 is a longitudinal sectional view of the same; and Fig. 3 is a sectional view taken on the line 3-3 of Fig. 2.

In the form of my improvements illustrated in the drawings, a porcelain housing 1, adapted to be supported as on a pole, has 70 a cap 2 cemented on its top and a hollow plug 3 cemented in its bottom.

A plate electrode 4 is fixed by the cap 2 on the body 1 and has a part 5 projecting beyond the body for connection beneath the 75 cap with the lead 6 to the line wire, the plate-electrode being provided with the clips 7 extending downwardly therefrom so as to form a seat disposed centrally of the top of the housing.

A resistance rod 8, suitably of carborundum, has its top frictionally engaged in the seat formed by the clips 7 and its bottom engaged by a conducting clamp 9 which is provided with a bottom plate 10 and lugs 11, 85 a screw 12 passing through the lugs to fix the clamp on the rod.

An insulating bolt 13, suitably of fiber, passes through the clamp bottom 10, which engages the bolt head.

A dished metal disk or ring 14 is placed with its bottom or central portion in engagement with the bottom of the clamp and on the bolt, the disk having the downwardly projecting circular ridge 14'. An insulator 15 is sleeved on the bolt in engagement with the body of the disk 14, within its ridge 14', the insulator containing the socket 15'. A dished metal disk 16 is passed over the bolt, into engagement with the insulator 15, 100 with its circular rib 16' disposed toward the concentric rib 14' so as to form a spark gap therewith. A second similar disk 16 is placed on the bolt with its body in engagement with the body of the first disk 16 and 105 its rib 16' disposed oppositely thereto. An insulator 17 is sleeved on the rod in engagement with the body of the second disk 16.

and within the rib 16' thereon, this insulator having a reduced part 17' which passes through the disks 16 and into the socket 15'.

Further disks 16 and insulators 17 are sleeved on the bolt, to a terminal disk 14'', the latter being clamped in place by an engaging or conducting stem 19 having a head 20 which screws on the bolt and clamps together the part through which such bolt passes.

A metal tube 21 is centrally disposed in the housing bottom 3, concentrically with the terminal 19 with which it forms an air gap, and a conducting plate 22, formed with the tube 21, is seated in the recess 3' of the bottom 3 and connected with the ground wire 23. A sectional insulating spider 24 is seated in the recess 3' in engagement with the stem 19 to hold the latter centrally in the tube 21.

As the resistor is movable longitudinally in the seat in which its top is engaged and as the resistor, dished plate electrodes, separating insulators, tie bolt and conducting stem are fixed together and are supported on the bottom spider, the expansion and contraction of these means through which the electrical discharges pass do not affect the housing. The parts forming the path for the discharge through the housing are, moreover, more readily assembled than heretofore and better registration of the parts is effected.

When the line is overcharged, a discharge to ground takes place through the parts 6, 4, 8, 9, 14, 16, 14'', 19, 21 and 23, the resistor and air gaps between the electrically separated electrodes serving to stop the flow of line current following a light discharge. In case of a heavy discharge, so that the normal current would follow through the path formed by the ionized air between the gaps due to the discharge, the heat generated by the current passing through the resistor and by the arcs across the air gaps between the electrodes, expands the air in the housing and produces a high velocity blast through the tubular electrode which destroys the conducting path and prevents the discharge of normal current, the amount of heat generated and the consequent force of the blast increasing with the voltage of the discharge and the work to be done in preventing the following current flow.

Having described my invention, I claim:

1. A lightning arrester comprising a housing containing a fluid chamber having an outlet, a conductor provided with engaging means in said housing, a resistor engaged by said means, conducting and insulating devices forming one or more air gaps in series with said resistor, means comprising an insulating bolt whereby said devices are tied to said resistor, a conducting terminal connected by said bolt in series with said gap

or gaps, and a conductor connected with said housing so as to form an air gap with said terminal in said outlet.

2. A lightning arrester comprising a housing containing a fluid chamber provided with an outlet, a conductor provided with engaging means in said housing, a resistor engaged by said means in said housing, means comprising conductors forming one or more air gaps in said housing, insulating means for tying said conductors to said resistor, a conducting terminal in series with said air gap or gaps, and a conductor combined with said terminal to form an air gap in said outlet. 80

3. In a lightning arrester, the combination of a housing having a restricted outlet, means comprising a conductor disposed in said outlet, a second conductor co-operating with said conductor first named to form an air gap, a plurality of electrodes disposed in said housing so as to form one or more air gaps adapted to produce electric arcs, a resistor, and insulating mechanism whereby said second conductor, said electrodes and 90 said resistor are tied together. 85

4. In a lightning arrester, the combination of a housing containing a chamber having a restricted outlet, conductors having an air gap between them in the path of a blast through said outlet, insulated conducting devices in said chamber, a resistor, and means comprising an insulating tension member for fixing together one of said conductors first named, said devices and said resistor. 100

5. In a lightning arrester, the combination of an insulating housing containing a chamber having a restricted outlet, conductors having an air gap between them in the path of a blast through said outlet, dished 105 conducting plates forming one or more air gaps in said chamber, and insulating means for separating said plates and tying them to one of said conductors.

6. In a lightning arrester, the combination of an insulating housing containing a chamber having a restricted outlet, conductors having an air gap between them in the path of a blast through said outlet, an insulating rod fixed to one of said conductors, 115 electrodes on said rod, and insulating means on said rod between said electrodes.

7. A lightning arrester comprising an insulating housing containing an outlet, a conductor seated in the bottom of said housing, 120 a conducting stem combined with said conductor first named to form an air gap in the path of a blast through said outlet, an insulating rod connected to said stem, a resistor connected to said rod, and plate electrodes 125 and insulators on said rod forming air gaps.

8. A lightning arrester comprising a housing containing a fluid chamber having an outlet at an end thereof, a conductor provided with engaging means fixed at the op- 130

- posite end of said housing, a resistor engaged by said means so as to be movable relatively thereto by contraction and expansion, conducting and insulating devices 5 forming one or more air gaps in series with said resistor, means comprising an insulating bolt passing through said devices whereby they are fixed to said resistor, a stem providing a conducting terminal connected 10 with said bolt in series with said gap or gaps, said stem having a part thereof connected in bearing relation with a part of said housing, and a conductor connected with said housing so as to form an air gap with said 15 terminal in said outlet.
9. A lightning arrester comprising a casing containing a fluid chamber having a restricted outlet, in combination with means comprising a resistor disposed in said chamber, conductors having an air gap between them in said chamber, and conductors to which current flows from said resistor and conductors first named and having an air gap between them in the path of fluid forced 20 through said outlet by expansion of air in said chamber resulting from heat generated by said resistor and an arc between said conductors first named.
10. A lightning arrester comprising a casing containing a chamber in combination with means comprising an electrode having an opening theréin providing an outlet from said chamber, an electrode coöperating with said electrode first named to form an air 25 gap, and means for expanding air in said chamber so as to cause a blast through said air gap.
11. A lightning arrester comprising a casing containing a chamber having a restricted outlet in combination with means comprising a conductor disposed in said outlet, a second conductor coöperating with said conductor first named to form an air gap, and a plurality of electrodes disposed in said 30 case so as to form a plurality of air gaps adapted for producing electrical arcs, said 35 second conductor connected within said case with one of said electrodes, whereby air in said chamber is heated and discharged across said air gap. 50
12. In apparatus of the character described, a casing containing a chamber having a restricted outlet in combination with means comprising conductors disposed in said outlet with an annular passage between them, and means comprising resistance and conductors forming air gaps whereby an electrical discharge produces heat and an air blast through said passage. 55
13. In apparatus of the character described, a casing containing an air chamber in combination with means comprising a tubular electrode forming a passage through which air is discharged from said chamber, an electrode disposed in said electrode first 60 named, means for centering said electrode second named in said electrode first named, and means for causing a blast through the gap between said electrodes. 65
14. In apparatus of the character described comprising an insulating casing containing an air chamber, a conductor fixed in said chamber, said conductor having means for frictionally engaging a detachable conductor, a conductor comprising non-inductive resistance detachably connected with said conductor first named, a set of conductors separated by insulating means so as to form air gaps, one of said sets of conductors being electrically connected with said 70 conductor second named, a stem connected to one of said sets of conductors, said case having internal means for holding said stem and set of conductors in place, and a conductor fixed in said case, said conductor last 75 named having a member coöperating with said stem to form an air gap in an outlet from said chamber. 80
- In testimony whereof I have hereunto set my name this 12th day of July, 1917.
- JOHN ROBERT MCFARLIN.
